(57) **CLAIM**

The ornamental design for a spring assembly as a part of a hand grip exerciser as shown and described.

DESCRIPTION

FIG. 1 is a perspective view of the spring assembly as a part of a hand grip exerciser according to embodiments herein;

FIG. 2 is a front view of FIG. 1;

FIG. 3 is a rear view of FIG. 1;

FIG. 4 is a left-side view of FIG. 1;

FIG. 5 is a right-side view of FIG. 1;

FIG. 6 is a top plan view of FIG. 1; and,

FIG. 7 is a bottom plan view of FIG. 1.

The present design includes features in broken lines that form no part of the claimed design.

1 Claim, 7 Drawing Sheets
